Inventor

Otis W. Ormsby

By *Lester L. Sargent*

Attorney

UNITED STATES PATENT OFFICE.

OTIS W. ORMSBY, OF HILL CITY, SOUTH DAKOTA.

WRENCH.

Application filed October 27, 1922. Serial No. 597,379.

To all whom it may concern:

Be it known that I, OTIS W. ORMSBY, a citizen of the United States, residing at Hill City, in the county of Pennington and State of South Dakota, have invented a new and useful Wrench, of which the following is a specification.

The object of my invention is to provide an improved wrench for tightening the bolts that secure fish plates to rails, and particularly to provide a device of this kind having novel means for adjustment of the operating lever. I attain these and other objects by the mechanism shown in the accompanying drawings, in which—

Figure 1 is a side elevation of my invention in use;

Fig. 2 is a section on line 2—2 of Fig. 1; and

Fig. 3 is a side elevation of the invention from the reverse side of that shown in Fig. 1.

Like numerals designate like parts in each of the several views.

Referring to the accompanying drawings, I provide opposite plates 1 and 4, rigidly connected by the metal straps 3 which extend across the rail. Mounted in spaced relation to plate 4 is a slotted arcuate plate 5 mounted on bolts or rivets 6. Plate 4 is provided with an arcuate slot 8 with which the arcuate slot 7 of plate 5 is aligned. I provide an operating wrench member or handle 9 having a longitudinal slot 10, through which extends the bolt 11 which is mounted in slots 7 and 8 in which it is slideable throughout the entire arc of the slots. Wrench member 9 is provided with a wrench head 12 adapted to engage the nut B of bolt A.

As shown in Figs. 2 and 3, I provide a suitable slot 13 in plate 1 to receive the head of the bolt which is to be tightened. To prevent the bolt from working out of place I provide a strap 2 attached to the exterior portion of plate 1 and extending across the opening 13 to engage the outer surface of the head of the bolt A, as shown in Fig. 2.

The operation of the device will be understood from the foregoing description in connection with the accompanying drawings. The device is positioned over the top of the rail with the slot 13 receiving the bolt head. The wrench handle 9 is operated manually, being slid longitudinally on member 11 until the head 12 engages a nut. The

wrench handle is then manually operated throughout an arc equal to that of slots 7 and 8, permitting of a wide range of operation, as shown.

What I claim is:

1. A wrench of the class described, comprising spaced plates, straps of suitable length to extend across the top of the rail on which the wrench is used said straps being affixed to the spaced plates, one of the plates having an arcuate slot, said slot extending through an arc of approximately 90 degrees, a third plate riveted to said slotted plate said third plate having a similarly aligned slot, a wrench handle, and a bolt extending through the wrench handle and through the slots in the aforesaid slotted plates, the bolt being slideable in the slots to permit of manual operation of the wrench.

2. A wrench of the class described, comprising spaced plates, one of the plates being slotted to receive the head of a bolt, straps rigidly connecting said plates, one of the plates extending substantially above the rail on which the wrench is used and having an arcuate slot, said slot extending through an arc of approximately 90 degrees, a spaced slotted guide plate having a like arcuate slot aligned with the first mentioned arcuate slot, a wrench handle, a bolt extending through the arcuate slots and through the wrench handle to operatively connect the wrench handle with the plates, the bolt being slideable in the arcuate slots, and a slot in the wrench handle extending longitudinally of the handle and through which the aforesaid bolt extends to permit of adjustment of the wrench handle to engage the nut to be tightened at varying positions relative to the top of the rail on which the wrench is mounted.

3. In a device of the class described, the combination of rail-engaging means, said means being slotted to engage the head of a bolt, spaced plates mounted on said means, said plates having arcuate slots extending through an arc of approximately 90 degrees, a wrench having a longitudinal slot in the handle thereof, a bolt slidably mounted in said slotted portion of the wrench handle and also slidably mounted in the arcuate slots of the spaced plates, whereby to permit a wide range of operative movement of the wrench.

4. In a device of the class described, the

combination of rail engaging means including means for engaging the head of a bolt, spaced plates affixed to said rail-engaging means, said plates having arcuate slots therein, a wrench having a slot extending longitudinally of the handle thereof and extending to a position opposite the aforesaid ar-

cuate slots when the wrench is in use, a bolt slidably mounted in all the aforesaid slots and extending through the slotted portion 10 of the wrench handle, for operation as herefore described and shown.

OTIS W. ORMSBY.
